UNITED STATES PATENT OFFICE.

WILLIAM J. MOXLEY, OF CHICAGO, ILLINOIS.

DESIGN FOR A BUTTER OR OLEOMARGARIN PRINT OR BRICK.

SPECIFICATION forming part of Design No. 32,576, dated April 24, 1900.

Application filed March 28, 1900. Serial No. 10,554. Term of patent 14 years.

To all whom it may concern:

Be it known that I, WILLIAM J. MOXLEY, a citizen of the United States, residing at Chicago, Illinois, have invented and produced a new and useful Design for Butter or Oleomargarin Bricks or Prints, of which the following is a specification.

In the drawings, Figure 1 represents a plan view of a butter-print, and Fig. 2 represents a sectional elevation taken in line 2 of Fig. 1.

As represented in the drawings, the butter or oleomargarin print or brick is provided

with a raised interior circular portion A, surrounded by a circular row of balls or beads B on a plain surface C.

What I regard as new, and desire to secure by Letters Patent, is—

The design for a butter or oleomargarin print or brick herein shown and described.

WILLIAM J. MOXLEY.
